UNITED STATES PATENT OFFICE.

ALLISON N. CLARK, OF PLAINVILLE, CONNECTICUT.

DESIGN FOR A GLOVE-BUTTONER.

SPECIFICATION forming part of Design No. 27,500, dated August 10, 1897.

Application filed March 15, 1897. Serial No. 627,699. Term of patent 7 years.

To all whom it may concern:

Be it known that I, ALLISON N. CLARK, a citizen of the United States, residing at Plainville, in the county of Hartford and State of Connecticut, have invented and produced a new and original Design for Glove-Buttoners, of which the following is a specification, reference being had to the accompanying sheet of drawings, showing a part thereof.

Figure 1 is a plan, and Fig. 2 an edge view, of a glove-buttoner showing my design, these views being deemed sufficient to fully illustrate said design.

The leading feature of my design consists in a flat surface, which, when viewed in plan, as in Fig. 1, is substantially like two abutting ovals inclosed by a continuous outline, one of said ovals being longer than the other and

provided with an opening that is defined by a line within and substantially parallel with the outline of said longer opening—that is to say, my design consists in the unitary article as shown in the accompanying drawings.

a indicates the smaller oval or handle portion of the glove-buttoner; *b*, the elongated oval or button-engaging portion of said buttoner, and *c* denotes the opening within said last-named oval portion.

What I claim is—

The design for a glove-buttoner as shown and described.

ALLISON N. CLARK.
